Attorney

UNITED STATES PATENT OFFICE.

HARRY H. CHANDLER, OF EAST PROVIDENCE, RHODE ISLAND, ASSIGNOR TO UNIVERSAL PRODUCTS CORPORATION, A CORPORATION OF RHODE ISLAND.

MANICURING IMPLEMENT.

1,362,601.

Specification of Letters Patent. Patented Dec. 21, 1920.

Application filed October 23, 1920. Serial No. 418,930.

To all whom it may concern:

Be it known that I, HARRY H. CHANDLER, a citizen of the United States, residing at East Providence, in the county of Providence and State of Rhode Island, have invented certain new and useful Improvements in Manicuring Implements, of which the following is a specification.

My device relates to a manicuring or chiropodic implement.

The essential objects of my invention are the removal of foreign accumulations from the inner and outer margins of the nail; to sever or depress the cuticle bordering the nail; to apply to the cuticle or nail or to both during the cleaning, cutting or depressing operation, an emollient or other liquid or fluid; to guide and distribute the liquid to and upon the area under treatment; to control the liquid supply; to prevent leakage; and to insure cleanliness of the implement.

To the above ends essentially my invention consists of such parts and in such combinations of parts as fall within the scope of the appended claims.

In the accompanying drawings which form a part of this specification,

Figure 1 is a side elevation of my implement,

Fig. 2, an enlarged vertical central section of a portion of the same in open position and with the cap removed,

Fig. 3, a section on line 3—3 of Fig. 2 showing the parts in closed position, and

Fig. 4, a like section of the same in open position showing the implement reversed and inclined.

Like reference characters indicate like parts throughout the views.

My device in the form thereof herein shown comprises a hollow glass receptacle 7 provided with an open tubular mouth 8 in which is mounted a resilient plug 10 of soft rubber engaging the mouth of the receptacle with sufficient tenacity to slightly resist against withdrawal. A portion of the plug extends beyond the receptacle, and the whole is provided with a central cylindrical longitudinal opening 12. Slidably embracing the extended portion of the member 12 is a glass cap or housing 14. The cap adheres in a slight degree to the plug 10. A cylindrical shaft 16 is provided consisting of an eduction portion 17 and an operating portion 18. The portion 17 of glass, wood, hard

rubber, or other material, comprises a shank 19 having a closed conical end 21. The shank is provided with a central longitudinal passage 22 communicating with a lateral opening 23 adjacent or in the enlargement 21. 60 The latter is longitudinally movable in the opening 12 of the plug. The enlargement 21 is, because of the plug, movable some distance within the latter to an extent which increases the pressure of the plug against 65 the mouth 8 of the receptacle insuring against leakage when the parts are in closed position. An annular external rib 25 on the shank furnishes a manual hold for longitudinally reciprocating the eduction portion 17 in the plug.

The operating portion 18 of the shaft is cylindrical and continuous with the eduction portion 17. It is provided with a central longitudinal passage 27 continuous with 75 the passage 22. The outer end of this portion has an elliptical inclined or beveled face 28 extending to flattened point 29. This face serves to guide and distribute the liquid issuing from the passage 27 concentric with the face. When the operating portion 18 is non integral with the eduction portion 17, as herein shown, the former comprises a body 31 provided with a shoulder 32 resting upon the shank 19, and an extension 34 frictionally engaging the inner face of said shank. The portion 18 in this instance is of orange wood, and is manually removable for substitution for sanitary purposes. 90

When the device is in use for operating upon the cuticle it is desirable that the liquid contents 36 of the receptacle be supplied to the face 28 and point 29. In such case the shaft 16 is manually moved through the plug 10 from the position shown in Fig. 3 to that shown in Fig. 4, disclosing the opening 23, and the whole implement reversed in position.

I claim:

1. In an implement of the character described, a receptacle, a plug in the receptacle, a shaft closed at its inner end slidably mounted in the plug and provided with a longitudinal passage and with a lateral 105 opening extending to the passage, and a beveled point upon its outer end.

2. In an implement of the character described, a receptacle, a resilient plug provided with a smooth face engaging the wall 110

of the receptacle and provided with a cylindrical opening, a shaft longitudinally movable in the opening and having a conical enlargement upon its inner end within the 5 receptacle, said shaft being provided with a passage and with a lateral opening communicating with the passage, and an operating point on the outer end of the shaft.

3. In an implement of the character described, a receptacle, a plug in the receptacle, a shaft traversing the plug provided with a central longitudinal passage, and a point upon the end of the shaft provided with an inclined face concentric with the 15 passage.

4. In an implement of the character described, a receptacle for a liquid, a plug frictionally positioned in the receptacle, and projecting beyond the end of the receptacle, a shaft frictionally positioned in the plug and provided with a longitudinal passage for the liquid, a point upon the end of the shaft provided with an inclined face to receive the liquid, and a cap inclosing the 20

point adapted to frictionally embrace the projecting portion of the plug.

5. In an implement of the character described, a receptacle, a plug in the receptacle, a shaft slidably mounted in the plug provided with a longitudinal passage and 30 with a lateral opening communicating therewith near its inner end, an external shoulder upon an intermediate portion of the shaft, and a point upon the outer end.

6. In an implement of the character described, a receptacle, a plug in the receptacle, a shaft comprising a hollow eduction portion slidably mounted in the plug and provided with a central passage communicating with the receptacle, and an operating 35 portion comprising a body provided with an inclined end face, and with an extension frictionally located in the eduction portion, said body and extension being provided with a central longitudinal passage. 40 45

In testimony whereof I have affixed my signature.

HARRY H. CHANDLER.
